UNITED STATES PATENT OFFICE

1,935,432

ELECTROHYDRAULIC OPERATING
MECHANISMLawrence S. Bourst, Schenectady, N. Y., assignor
to General Electric Company, a corporation of
New York

Application April 29, 1932. Serial No. 668,268

19 Claims. (CL. 60—52)

My invention relates to an electro-hydraulic operating mechanism and is an improvement over the type described in the copending application of William J. Woods, Serial No. 485,474, filed September 30, 1930, now Patent Number 1,901,620, and assigned to the same assignee as the present invention.

In mechanisms of the above type a vertical casing or cylinder containing a fluid such as oil has mounted therein a piston which moves between two positions within the cylinder and is biased to one of these positions. An impeller type pump having intake and exhaust passages communicating with opposite sides of the piston is mounted at one end of the casing and forces fluid from one side of the piston to the other side of the piston to move the same within the casing. The pump is driven by means of an electric motor mounted on top of the casing. When the pump is operated, the piston in response to the developed pressure differential is moved from the biased position to another position and when operation of the pump is stopped, the piston returns to its biased position. The piston is connected by means of push rods extending from the casing to a cross-head carrying a work-engaging member.

In some applications of this electro-hydraulic operating mechanism it is desirable to control the rate of movement of the piston in either or both directions and to vary this rate, and to do this without affecting the characteristics of the pump.

It is a principal object of my invention to provide an electro-hydraulic operating mechanism in which the rate of movement of the piston may be controlled and in either direction or both directions.

It is another object of my invention to provide an electro-hydraulic operating mechanism in which the rate of movement of the piston may be controlled in either direction or both directions without affecting the characteristics of the pump, particularly the pressure head developed by the pump.

It is still another object of my invention to provide an electro-hydraulic operating mechanism in which the rate of movement of the piston in either direction or both directions may be varied.

These and other objects will appear herein-after.

Referring to the drawing, Fig. 1 is a cross-section of my improved electro-hydraulic operating mechanism taken on the section line 1—1 of Fig. 2; Fig. 2 is a top view of my electro-hy-

draulic operating mechanism with the cover broken away of Fig. 1; and Fig. 3 is a cross-section of my electro-hydraulic operating mechanism taken on the section line 3—3 of Fig. 1.

In the preferred embodiment of my invention, I provide a vertical casing containing a fluid such as oil having a pump mounted in the lower end thereof. The impeller of the pump is driven by means of an electric motor mounted on the cover of the casing. The intake to the impeller housing extends upwardly through the piston. The piston has mounted thereon push rods extending through the casing and supporting a work engaging crosshead. The piston is biased to a position adjacent the pump and is moved upwardly in response to pressure developed by the pump when fluid is taken from above the piston and forced to the under side of the piston. When the motor driving the pump is deenergized, no pressure is developed and the piston returns to its biased position forcing the fluid back through the pump from the under side of the piston to the upper side of the piston.

In order to retard movement of the piston from its operating position to its biased position, I provide a baffle plate which cooperates with the exhaust of the pump and which is biased to partially close the exhaust. It is free to move to an open position when pressure is developed by the pump so that it will not affect the pressure developed by the pump. When the motor is deenergized and the piston returns from the operating position to the biased position, this baffle member moves to partially close the exhaust to limit the flow of fluid back through the pump. This, of course, retards the movement of the piston to biased position. The biased position of the baffle plate may be varied by means of an adjusting screw or rod connected to the baffle plate and extending through the cover. This varies the fluid flow and hence the rate of movement of the piston from operating position to biased position.

In order to vary the movement of the piston during its power stroke from its biased position to its operating position, I provide another adjustable baffle plate cooperating with the intake to the impeller pump housing. This limits the amount of fluid entering the pump housing but does not affect the pressure head so that although the rate of movement of the piston may be varied, its working thrust is not affected. Adjusting rods are provided for adjusting the position of this baffle.

The reason why the pressure developed by the

pump is not affected by the position of the intake baffle plate, is that the pressure exerted by the piston in the fluid between the exhaust and the piston is balanced by the pressure developed by the pump at all times. Therefore, regardless of the quantity of fluid pumped by the pump from one side of the piston to the other, the pressure developed by the pump will not be affected. It will be seen, therefore, that the only effect of increasing or decreasing the flow of fluid through the pump will be to increase or decrease the rate of movement of the piston within the casing.

Referring to the drawing, in Fig. 1 the fluid casing 10 has mounted therein the piston 11 which is shown in its biased position adjacent the pump housing 13. The pump housing has mounted therein the impeller 12 which develops the pressure for raising the piston. The pump housing is provided with the intake 14 connected with the inlet oil tube 15, which is connected to the bearing bracket 16 supporting the inlet member 17 connected to the oil tube. This bracket member 16 is connected to the cover 18 of the fluid casing 10. The impeller 12 receives oil on both sides through the openings 19 and 20 and expels the oil through exhaust passage 24.

The impeller pump 12 is mounted on the shaft 21 supported in bearings 22 and 23. The bearing 22 is supported by the pump housing and the bearing 23 is supported by the cover 18. The shaft is connected to the electric motor 35 by means of the coupling 36, the motor being supported on the cover 18 by legs 37. A cover 38 is provided for the motor and has ventilating openings 38' therein.

The pump housing has concentric therewith a sleeve 35 which cooperates with the exhaust passage of the pump to form an annular exhaust outlet passage 26 surrounding the pump housing. Resting upon this sleeve and cooperating with the exhaust passage is a baffle plate 27 which is biased toward a closed position by means of the spring 28 mounted on the stud 29. The plate is maintained in a partially opened position by means of the rod 30 supported by the cover 18 at 32. This rod may be adjusted in a vertical direction to vary the opening between the plate 27 and the exhaust opening 26.

When fluid is forced through the pump from the upper side of the piston to the under side of the piston to raise the same the plate 27 is free to move against its bias in an upward direction in response to the pressure developed in the fluid and this prevents retardation of the flow of fluid to the under side of the piston. When the piston resets, however, the plate returns to its partially closed position and limits the flow of fluid back through the pump. This, of course, retards the return of the piston to biased position.

Mounted adjacent the inlet member 17 is a second baffle plate 34 supported on the adjustable rods 33. These rods are adjustable in the vertical direction to vary the opening between the inlet member 17 and the plate 34. I have found that by varying the opening and thus varying the flow of fluid through the inlet of the pump housing, I am able to vary the rate of movement of the piston from its biased position to its operating position without affecting the pressure head developed by the pump 12. Since the baffle plate 34 is free to move in a vertical direction away from the inlet member 17 when the fluid passes back through the pump and through the

inlet and oil tube 15 to the upper side of the piston, free flow of fluid from the oil tube is not interfered with by the baffle plate.

The piston has mounted thereon the four push rods 39 supporting the cross-head 40 which carries the work-engaging member 41. These push rods pass through bushings 39', shown in Fig. 3 mounted in the bracket member 16.

In operation when the electric motor 35 is energized fluid is drawn down through the inlet member 17 and oil tube 15 to the inlet 14 of the pump housing. The rate of flow is dependent upon the opening between the plate 34 and inlet member 17. The fluid enters the impeller 12 through the openings 19 and 20 and is forced out through the exhaust passage 24 to the exhaust opening 26. In response to the pressure developed the plate 27 moves away from the exhaust passage 26 against the bias of spring 28. This permits the flow of oil to the under side of the piston and in response to the pressure there developed, moves the piston 11 from the biased position shown, to an upper position. As has been pointed out, by varying the opening between the inlet member 17 and the baffle plate 34, the amount of fluid per unit of time forced from the upper side of the piston to the under side of piston may be varied. This varies the rate of movement from the biased position to the upper position. This, however, does not affect the pressure head developed by the pump.

By increasing the distance between the inlet member 17 and the baffle plate 34, the quantity of fluid which can be pumped through the pump housing to the under side of the piston is increased, thereby increasing the rate of movement of the piston during the power stroke.

By decreasing the distance between the inlet member 17 and the baffle plate 34 the quantity of fluid is decreased and hence the rate of movement of the piston from its biased position to its operating position is decreased.

When the motor 35 is deenergized the piston returns to its biased position. When the pressure developed by the pump falls off as the impeller and motor come to rest, the baffle plate 27 returns to its partially closed position and retards the flow of oil from the under side of the piston back through the pump through the oil inlet tube 15 to the upper side of the piston. By increasing the opening between the baffle plate 27 and exhaust passages, the flow of fluid back through the pump is increased and thereby the rate of movement from its operating position to its biased position is increased. By decreasing this opening the rate of movement is decreased. Since the baffle plate 34 is free to move away from the inlet 17, the free flow of fluid from the intake side of the pump is not interfered with and the rate of movement of the piston to biased position is controlled only by the baffle plate 27.

The embodiment of the invention illustrated and described herein has been selected for the purpose of clearly setting forth the principles involved. It will be apparent, however, that the invention is susceptible of being modified to meet the different conditions in its use and I, therefore, aim to cover by the appended claims all modifications within the true spirit and scope of my invention.

What I claim as new and desire to secure by Letters Patent of the United States, is,—

1. A hydraulic operating mechanism, including a casing for containing a fluid, a piston therein movable between two positions and biased to one

of said positions, a pump in said casing having intake and exhaust passages communicating with opposite sides of the piston for forcing fluid from one side of said piston to the other side of said 5 piston to move said piston from the biased position to another position, said pump being adapted to permit a reverse flow of fluid therethrough when said piston returns from said other position to said biased position, and means cooperating 10 with the intake of said pump to control the flow of fluid to said pump whereby the rate of movement of said piston from said biased position to said other position may be retarded said means cooperating with said intake permitting a free 15 flow of fluid from said intake when said piston returns from said other position to said biased position.

2. A hydraulic operating mechanism, including a casing for containing fluid, a piston therein 20 movable between two positions and biased to one of said positions, an impeller pump in said casing having intake and exhaust passages communicating with opposite sides of the piston for pumping fluid from one side of said piston to the other side of said piston to move said piston from the biased position to another position, and means cooperating with the intake of said pump for controlling the rate of movement of said piston from the biased position to the other position, 25 said means cooperating with said intake permitting a free flow of fluid from said intake when said piston returns from said other position to said biased position.

3. A hydraulic operating mechanism, including a casing for containing a fluid, a piston therein 30 movable between two positions and biased to one of said positions, a pump in said casing having intake and exhaust passages communicating with opposite sides of said piston for forcing fluid from one side of said piston to the other side of said piston to move said piston from the biased position to another position, said pump being adapted to permit a reverse flow of fluid therethrough when said piston returns from said other position to said biased position, and means cooperating 35 with the intake of said pump for restricting the flow of fluid to said intake but permitting free flow from said intake whereby movement of said piston only from said biased position to said other position will be retarded.

4. A hydraulic operating mechanism, including a casing for containing a fluid, a piston therein 40 movable between two positions and biased to one of said positions, a pump in said casing having intake and exhaust passages communicating with opposite sides of said piston for forcing fluid from one side of said piston to the other side of said piston to move said piston from the biased position to another position, said pump being adapted 45 to permit a reverse flow of fluid therethrough when said piston returns from said other position to said biased position, means cooperating with the intake of said pump for controlling the flow of fluid from one side of the piston to the other side of the piston to control the rate of movement of said piston from its biased position to said other position, and means for adjusting said 50 cooperating means for varying the rate of movement of said piston from the biased position to said other position, said means cooperating with the intake of said pump permitting a free flow of fluid from said intake when said piston returns from said other position to said biased position.

5. A hydraulic operating mechanism, including 55 a casing for containing a fluid, a piston therein

movable between two positions and biased to one of said positions, an impeller pump in said casing having intake and exhaust passages communicating with opposite sides of said piston for forcing fluid from one side of said piston to the other 60 side of said piston to move said piston from the biased position to another position, a movable plate cooperating with said intake for controlling the opening to the intake to control the flow of fluid from one side of the piston to the other whereby the rate of movement of said piston from the biased position to said other position may be controlled, and means extending to the exterior of said casing for adjusting the position of said plate with respect to the intake of said pump 65 for varying the rate of movement of said piston, said movable plate permitting a free flow of fluid from said intake when said piston moves from said other position to said biased position.

6. A hydraulic operating mechanism, including a casing for containing a fluid, a piston therein 70 movable between two positions and biased to one of said positions, a pump in said casing having intake and exhaust passages communicating with opposite sides of the piston for pumping fluid from one side of said piston to the other side of said piston to move said piston from the biased position to another position, said pump being adapted to permit a reverse flow of fluid therethrough when said piston returns from said other 75 position to said biased position, means cooperating with the intake of said pump for controlling the rate of movement of said piston from the biased position to the other position, and means cooperating with the exhaust of said pump for controlling the rate of movement of said piston from the other position to its biased position.

7. A hydraulic operating mechanism, including a casing for containing a fluid, a piston therein 80 movable between two positions and biased to one of said positions, a pump in said casing having intake and exhaust passages communicating with opposite sides of the piston for forcing fluid from one side of said piston to the other side of said piston to move said piston from the biased position to another position, said pump being adapted to permit a reverse flow of fluid therethrough when said piston returns from said other position to said biased position, means cooperating with said intake for restricting the flow of fluid to said intake but permitting free flow from said intake whereby movement of said piston from said biased position to said other position is retarded, and other means cooperating with said exhaust for permitting free flow of fluid from said exhaust 85 but restricting flow to said exhaust passage whereby movement of said piston from said other position to said biased position is retarded.

8. A hydraulic operating mechanism, including a casing for containing fluid, a piston therein 90 movable between two positions and biased to one of said positions, a pump in said casing having intake and exhaust passages communicating with opposite sides of said piston for forcing fluid from one side of said piston to the other side of said piston for moving said piston from the biased position to another position, said pump being adapted to permit a flow of fluid therethrough from said exhaust to said intake when said piston returns from said other position to said biased 95 position, and means cooperating with the intake of said pump for controlling the flow of fluid to said pump to control the rate of movement of said piston from said biased position to said other position, and other means cooperating with the 100

- exhaust of said pump for controlling the flow of fluid back through said pump from said other side of said piston to said one side of said piston when said piston returns from said other position to said biased position, and means for varying the position of said means cooperating with the exhaust of said pump whereby the rate of movement of said piston from said other position to its biased position may be varied.
- 10 9. A hydraulic operating mechanism, including a casing for containing fluid, a piston therein movable between two positions and biased to one of said positions, a pump in said casing having intake and exhaust passages communicating with opposite sides of said piston for forcing fluid from one side of said piston to the other side of said piston for moving said piston from the biased position to another position, said pump being adapted to permit a flow of fluid therethrough from said exhaust to said intake when said piston returns from said other position to said biased position, means cooperating with the intake of said pump for controlling the flow of fluid to said pump to control the rate of movement of said piston from said biased position to said other position, and other means cooperating with the exhaust of said pump for controlling the flow of fluid back through said pump from said other side of said piston to said one side of said piston when said piston returns from said other position to said biased position, means for varying the position of said means cooperating with the intake of said pump whereby the rate of movement of said piston from its biased position to said other position may be varied, and other means for varying the position of said means cooperating with the exhaust of said pump whereby the return movement of said piston from said other position to its biased position may be varied.
- 40 10. A hydraulic operating mechanism, including a casing for containing a fluid, a piston in said casing movable between two positions and biased to one of said positions, an impeller pump in said casing having intake and exhaust passages communicating with opposite sides of said piston for forcing fluid from one side of said piston to the other side of said piston to move said piston from the biased position to another position, a movable baffle plate cooperating with the exhaust of said pump and biased to partially close said exhaust and movable from the partially closed position to a fully opened position in response to pressure developed by said pump when said piston moves from said biased position to the other position and movable back to the partially closed position when said piston returns from said other position to said biased position to control the flow of fluid back through said pump to control movement of said piston from said other position to said biased position, and an adjusting rod extending from said plate to the exterior of said casing for varying the partially closed position of said plate whereby the rate of movement of said piston from said other position to said biased position may be varied.
11. A hydraulic operating mechanism, including a casing for containing a fluid, a cover for said casing, a piston in said casing movable between two positions and biased to one of said positions, an impeller pump in said casing having intake and exhaust passages communicating with opposite sides of said piston for forcing fluid from one side of the piston to the other side of said piston to move said piston from the biased position to another position, an adjustable plate co-
- operating with the exhaust of said pump for controlling the flow of fluid back through said pump from said other side of said piston to said one side of said piston to control the rate of movement of said piston from said other position to said biased position, an adjusting means for said plate to vary the opening between said plate and said exhaust passage whereby the rate of movement of said piston from said other position to said biased position may be varied, said adjusting means being supported by said cover and extending through said piston and cover.
12. A hydraulic operating mechanism including a casing for containing a fluid, a cover for said casing, a piston in said casing movable between two positions and biased to one of said positions, an impeller pump in said casing having an intake passage extending through said piston and an exhaust passage for forcing fluid from one side of said piston to the other side of said piston for moving said piston from its biased position to another position, a movable baffle plate cooperating with the exhaust passage of said pump, means for biasing said plate to partially close said exhaust passage, said plate being movable to an open position in response to the pressure created by said pump when said piston is moved from its biased position to another position, said plate moving back to its partially closed position to control the flow of fluid back through said pump when said piston moves from said other position to its biased position to control the rate of movement of said piston, and an adjusting rod supported by said cover and connected to said plate for varying the partially closed position of said plate for varying the rate of movement of said piston from said other position to its biased position.
13. A hydraulic operating mechanism including a casing for containing fluid, a cover for said casing, a piston in said casing movable between two positions and biased to one of said positions, a motor mounted on said cover, a pump in said casing driven by said motor and having an intake including an oil tube extending through said piston and having an exhaust, said intake and exhaust communicating with opposite sides of said piston, said pump forcing fluid from one side of said piston to the other side of said piston to move said piston from the biased position to another position, said pump being adapted to permit a reverse flow of fluid therethrough when said piston returns from said other position to said biased position, a baffle plate cooperating with the exhaust of said pump for controlling the flow of fluid through said pump to control the rate of movement of said piston from said other position to said biased position, said plate being biased to partially close said passage, an adjusting rod connected to said plate to vary the opening between said plate and the exhaust of said pump whereby the rate of movement of said piston from said other position to said biased position may be varied, said rod being supported by said cover and extending through said piston and cover to the exterior of said casing.
14. A hydraulic operating mechanism including a casing for containing fluid, a cover for said casing, a piston in said casing movable between two positions and biased to one of said positions, a motor mounted on said cover, an impeller pump in said casing driven by said motor and having intake and exhaust passages, an oil tube connected to said intake and extending through said piston, said tube and exhaust communicating with

- opposite sides of said piston, said pump when operating forcing fluid from one side of said piston to the other side of said piston for moving the piston from its biased position to another position, a tilttable baffle plate cooperating with the exhaust of said pump for controlling the flow of fluid through said pump to control the rate of movement of said piston from said other position to said biased position, and means for biasing 5 said plate to partially close the exhaust of said pump, a rod supported by said cover and extending therethrough and through said piston and connected to said plate to vary the opening between said plate and the exhaust of said pump 10 whereby the rate of movement of said piston from said other position to said biased position may be varied.
15. A hydraulic operating mechanism including a casing for containing fluid, a cover for said casing, a piston in said casing movable between two positions and biased to one of said positions, a motor mounted on said cover, a pump in said casing connected to said motor to be driven thereby, said pump having intake and exhaust passages, an oil tube extending through said piston and connected with the intake of said pump whereby fluid may be drawn from one side of said piston through said tube and forced to the other side of said piston through said exhaust passage 20 to move the piston from its biased position to another position when said motor is energized to drive said pump, said pump being adapted to permit a flow of fluid therethrough from said exhaust to said intake when said motor is deenergized and 25 said piston returns from said other position to said biased position, a sleeve concentrically mounted with respect to said pump and cooperating with the exhaust of said pump to form an annular exhaust opening, a movable baffle plate 30 cooperating with said pump and sleeve to control said annular exhaust opening for controlling the flow of fluid through said pump to control the rate of movement of said piston from said other position to said biased position, resilient means 35 for biasing said plate to partially close said exhaust opening, an adjusting rod connected to said plate for varying the partially closed position of said plate whereby the rate of movement of said piston from said other position to said biased 40 position may be varied, said adjusting rod being supported by said cover and extending through said cover and said piston to engage said plate.
16. A hydraulic operating mechanism including a casing for containing a fluid, a piston therein 45 movable between two positions and biased to one of said positions, a pump in said casing for forcing fluid from one side of said piston to the other for moving said piston from its biased position to another position, and having intake and exhaust passages, an oil tube extending through said piston and connected with the intake of said pump, a sleeve concentrically mounted with respect to said pump and cooperating with the exhaust of said pump for providing an annular 50 exhaust opening, said oil tube and exhaust opening communicating with opposite sides of said piston, said pump being adapted to permit a reverse flow of fluid therethrough when said piston returns from said other position to said biased 55 position, a baffle plate cooperating with said oil tube to control the flow of fluid to said pump in one direction to vary the movement of said piston from said biased position to the other position when said pump is energized, and a baffle plate cooperating with said exhaust opening for controlling the flow of fluid through said pump in the opposite direction to control the rate of movement of said piston from the other position to said biased position, and a rod connected to said plate cooperating with said exhaust opening and extending to the exterior of said casing for adjusting the position of said plate with respect to 60 said exhaust opening whereby the rate of movement of said piston from the other position to said biased position may be varied.
17. A hydraulic operating mechanism including a casing for containing a fluid, a piston therein 65 movable between two positions and biased to one of said positions, an impeller pump in said casing for pumping fluid from one side of said piston to the other for moving the piston from its biased position to another position and having intake and exhaust passages, an oil tube extending through said piston and connected with the intake of said pump, a sleeve concentrically mounted with respect to said pump and cooperating with the exhaust of said pump for providing an annular 70 exhaust opening, said oil tube and exhaust opening communicating with opposite sides of said piston, a baffle plate cooperating with said sleeve and pump for controlling the flow of fluid through said pump in the opposite direction to control the rate of movement of said piston from the other position to said biased position, and means for supporting said first plate adjacent said oil tube, said supporting means being adjustable to vary the opening between said oil tube and said first plate whereby the rate of movement of said piston from the biased position to said other position may be varied.
18. A hydraulic operating mechanism including a casing for containing a fluid, a piston therein 75 movable between two positions and biased to one of said positions, a pump in said casing for forcing fluid from one side of said piston to the other for moving said piston from the biased position to another position and having intake and exhaust 80 passages, an oil tube extending through said piston and connected with the intake of said pump, a sleeve concentrically mounted with respect to said pump and cooperating with the exhaust of said pump for providing an annular exhaust opening, said oil tube and exhaust opening communicating with opposite sides of said piston, said pump being adapted to permit a flow of fluid therethrough from said exhaust to said intake when said piston returns 85 from said other position to said biased position, a baffle plate cooperating with said oil tube to control the flow of fluid through said pump in one direction to vary the rate of movement of said piston from said biased position to the other position when said pump is energized, a baffle plate supported by said sleeve and pump and cooperating with said exhaust opening for controlling the flow of fluid through said pump in the opposite direction to control the rate of movement of said piston from the other position to said biased position, and a rod connected to said plate cooperating with said exhaust opening and extending to the exterior of said casing for adjusting the position of said plate with respect to 90 said exhaust opening whereby the rate of movement of said piston from the other position to said biased position may be varied.
19. A hydraulic operating mechanism including a casing for containing a fluid, a cover for 95 said casing, a piston therein movable between two positions and biased to one of said positions, an impeller pump in said casing for pumping fluid from one side of said piston to the other for moving said piston from the biased position to 100

another position and having intake and exhaust passages, an oil tube extending through said piston and connected with the intake of said pump, a motor on said cover for driving said pump, a sleeve concentrically mounted with respect to said pump and cooperating with the exhaust of said pump for providing an annular exhaust opening, said oil tube and exhaust opening communicating with opposite sides of said piston, 10 a baffle plate cooperating with said oil tube to control the flow of fluid through said pump in one direction to vary the rate of movement of said piston from said biased position to the other position; a baffle plate cooperating with said sleeve and pump for controlling the flow of fluid through said pump in the opposite direction to

control the rate of movement of said piston from the other position to said biased position, means for supporting said first plate adjacent said oil tube, said means being adjustable to vary the opening between said oil tube and said plate whereby the rate of movement of said piston from the biased position to said other position may be varied, and a rod supported by said cover and connected to said second plate cooperating with said exhaust opening, said rod extending to the exterior of said casing through said cover for adjusting the position of said plate with respect to said exhaust opening whereby the rate of movement of said piston from the other position to said biased position may be varied. 85
